GARMENT SUPPORTING ATTACHMENT

Clarence Knol, Grand Rapids, Mich.

Application April 6, 1936, Serial No. 72,923

2 Claims. (Cl. 223—88)

This invention relates generally to garment supports and particularly to garment supporting attachments adapted to be used in connection with coat hangers.

The primary object of this invention is to provide a simple, efficient and economical attachment for coat hangers which is easy to apply to a coat hanger and is simple to use, a garment being easily and quickly hooked onto the attachment with no liability of the garment becoming unhooked from the attachment, the weight of the garment causing the garment to be supported firmly. The attachment is made in a most economical manner, being made of wire and easily bent to the proper shape.

Another object of the invention is to provide a garment support which may be attached to a coat hanger which will hold a garment, such as a lady's skirt or men's trousers, in such a way that the garment will be held in a flat and smooth condition.

A still further object of the present invention is to produce a garment holding attachment for use on a wire coat hanger which will not slip endwise on the hanger during use. Slipping of the attachment endwise on the hanger would cause the garment to droop and wrinkle which would be very undesirable.

Another object of the invention is to provide means which prevents the attachment from raising relative to the hanger when a garment is inserted between the hook members of the attachment.

Other objects and advantages will appear during the following description taken in connection with the accompanying drawing, in which,

Fig. 1 is an elevation showing an ordinary wire coat hanger supplied with a pair of garment holding attachments having a pair of men's trousers hooked thereon and being pendant therefrom.

Fig. 2 is a view showing the horizontal rod member of the coat hanger in section having an attachment of my invention attached thereto.

Fig. 3 is a similar view showing the attachment in hooked position having a garment supported thereon.

Fig. 4 is a view showing a modified form of my invention.

Like reference numbers refer to like parts throughout the drawing.

As illustrated in Fig. 1, the reference number 1 refers to a wire coat hanger having the usual lower horizontal rod member 2 to which is attached a pair of garment supporting attach-

ments 3 of my invention, these being hooked to the cuff of a pair of men's trousers 4. The attachment is also adapted to support various garments such as a lady's skirt or certain dresses required to be held in a flat condition.

The attachment proper is formed of a single piece of wire and is bent to substantially inverted V-shape forming the legs 5. The vertex of a V-shaped portion is formed into substantially circular form, as indicated at 6, of the proper size 10 to fit over the rod member 2 of the wire coat hanger. This circular portion fits loosely on the rod when the attachment is not in use. Directly below this circular portion and adjacent the opening the attachment has inwardly bent portions 15 forming the detents 7 for yieldably holding the attachment down onto the rod member. The downwardly and outwardly extending legs 5 terminate at the lower ends in the inwardly and upwardly extending hooks 8 which are pointed at their ends and are normally spaced from each other. See Fig. 2.

In use a pair of the above described attachments are placed in spaced relationship on the lower horizontal rod portion of a wire coat hanger 25 and a garment, which it is desired to support, is located between the hooks 8. The detents prevent any upward movement of the attachment on a slight lifting tendency caused by the upward movement of the garment. These detents, or 30 some similar means, which would prevent the lifting of the attachments by slight upward urge, are quite essential as any upward movement of the attachment during insertion of the garment would be very undesirable.

When the garment is in the desired position the legs 5 are pressed toward each other thereby causing the hooks to pierce the garment and to bring the hooks in overlapping relationship. When the garment is released from manual support the weight of the garment holds the hooks 40 in their overlapping and hooked relationship by means of the angularity of the hooks.

When the hooks are in their overlapping position the attachments are held frictionally from 45 sliding lengthwise on the rod member of the hanger as a result of the circular portion 6 of the attachment being contracted around the rod member. This frictional engagement of the attachment on the rod member is desirable in 50 that the garment will be held in a flat and non-wrinkling condition when a pair of attachments are utilized in spaced relationship along the rod to support the garment as shown in Fig. 1.

The modified form of the invention as shown 55

in Fig. 4 has but one leg 5a terminating in a single hook member 8a. The circular portion 6a surrounds and frictionally engages the rod member 2. The upper end of the modified form of attachment terminates in a short finger 5b. Directly below and adjacent the circular portion 6a are formed the detents 7a which yieldably prevent upward movement of the attachment. This form of attachment is utilized quite similarly to the preferred form, having but a single hook means.

From the above description it will be seen that I have inventively created a device which is extremely simple to manufacture, is handy to use and one which will give satisfaction for the purposes for which it is intended.

Having thus fully described my invention what I claim and desire to secure by Letters Patent is:

I claim:

20 1. In combination with a coat hanger having a horizontal rod member, of a garment supporting attachment comprising, a length of wire bent to substantially inverted V-shape adapted to pass over and to be pendant from said rod, one leg of 25 the V-shaped portion depending each side of the rod member, means whereby said attachment is

held positively on said rod from downward movement and held yieldably from upward and longitudinal movement along said rod, the legs of said V-shaped portion terminating in hook portions.

2. In combination with a coat hanger having a substantially horizontal rod member, of a garment supporting attachment comprising, a resilient elongated element passing over said rod member, said element depending from both sides of said rod member, said depending portions being spaced from each other at all points and having inwardly extending hook members located in substantially the same plane, said hook members springing normally to maximum spaced relationship, said hooks yieldably moving toward one another to overlapping relationship when in hooked position to support a garment thereon, means for yieldably preventing upward movement of said attachment from said rod member at all times, means allowing sliding movement of said attachment on said rod when said hooks are in spaced relationship and means for frictionally preventing movement of said attachment along said rod member when said hooks are in hooked and overlapping position. 25

CLARENCE KNOL.
